HASP FASTENER FOR TRUNKS, BOXES, AND
THE LIKE

Hector Fridolin Baerfuss, Thun, Switzerland

Application January 29, 1936, Serial No. 61,359
In Austria June 17, 1935

1 Claim. (Cl. 292—281)

The present invention is a hasp fastening for trunks, boxes and the like and its object is to provide a simple, cheap and safe locking device adapted to be sealed if needed and not easily 5 damaged when the trunk is handled.

A constructional form of the invention is described and shown in the accompanying drawing.

- Fig. 1 is a plan view of the fastening.
- Fig. 2 is a side view of the fastening.
- Fig. 3 is a side view of the movable hinge.
- Fig. 4 is a plan view of a fastening plate.
- Fig. 5 is a side view of a fastening plate.
- Fig. 6 is a section on line A—B of Fig. 2.
- Fig. 7 is a spring with crossed arms.
- Fig. 7a is a side view thereof.
- Fig. 8 is a spring with parallel arms.
- Fig. 8a is a side view thereof.
- Fig. 9 is a view of a transport box.

The movable hinge strip 1 is hinged by means 20 of a pin 2 to a fast strip 3. On the inside of the movable hinge strip 1 a shoulder stud 4 having a conical head 5 is fixed and besides a flat spring 12 attached at one end and standing off from the plate 1 with the other end. Two plates 6 and 25 7 set apart at a certain distance from each other and held together to form a pocket are sunk into the front side of the trunk and inside of this pocket a U shaped spring having the ends of its legs projecting to the outside of the pocket is 30 held in position by a pin 8. This spring bears with its two arms against a stop pin 19 which keeps said arms separated from each other in close proximity of round openings 10 provided in plates 6 and 7. When closing the hinge strip the head 35 5 is pressed against the two arms of the U-shaped spring 9 the latter are spread apart, snap in behind the shoulder 11 of the head 5 fixing thereby the movable hinge strip 1 and locking up the box. On the inside of the fastening strip a spring 40 12 is fixed. The free ends 13 of arms of the spring 9 are extended into a recess provided in the trunk wall outside of the base plate 7, loops 45 16 being provided in said ends, which will register when the trunk is closed with a loop 14 formed by the rolled up end of the movable strip 1.

The opening of the trunk is effected by pressing the ends 13 of the spring 9 together to release the head 5. In this moment the hinge strip 1 is repelled by the spring 12 of the hinge strip 1 so that a self acting opening of the fastening takes place.

When closing the trunk the head 5 of the stud 4 of the movable strip 1 is introduced into the hole 10 of plate 6 and pressed down until the arms of spring 9 have snapped together behind head 5. The trunk is then locked and may be sealed by a cord having a lead attached thereto as sealing means 15 drawn through the loops 14, 16 to obtain the required security against an illicit opening.

The fastening according to the present invention may be called a safety fastening. The locking members are sealed directly, but the locking does not depend on the seal. Being sunk into a recess of the wall of the trunk and being hidden by the hasp the locking members will not suffer from handling during transport and the opening can always be effected without any tools.

Applicant is well aware that U shaped springs or spring controlled clamps closing upon a headed stud have already been used before and were 20 released either by hand or by a pressure upon certain parts of the structure. Applicant does not claim such mechanism as such, but the combination of a particular form of such a spring with 25 a hasp fastening for trunks and with means to protect the same against rough handling during transport.

What I claim is:

In a hasp fastener for trunks, boxes and the like of the kind having a hinge strip the movable member of which may be locked by spring arms embracing a shouldered head and in combination, the movable member of the hinge strip having a loop formed at its extreme end for sealing 30 purposes and a stud provided with a conical and shouldered head fixed to the inside of said member, a pocket formed of two plates held at a distance from each other, with holes in said plates to receive said stud and struck into the 35 front wall of the trunk, a pivot inserted between said plates and a V shaped spring held by said pivot and arranged to embrace said stud with its legs which extend to the outside of the pocket to permit being gripped when opening the hasp, 40 and a stop pin between the plates and between the legs of said spring to keep the legs of the latter separated to permit introducing the conical head of said stud, all substantially as described. 45
